SHOULDER CORD

Adolph Ostwald, Staten Island, N.Y.

Application November 25, 1958, Serial No. 53,528

Term of patent 14 years

(Cl. D3—32)

Fig. 1.

Fig. 2.

Figure 1 is a side elevation of a shoulder cord showing my new design; and

Figure 2 is a front elevation of same.

The braid continues around except for the bottom portion which is a single cord and is illustrated in dot and dash lines on the drawing for convenience of illustration.

I claim:

The ornamental design for a shoulder cord, as shown and described.
